UNITED STATES PATENT OFFICE.

PHILIP GENGEMBRE HUBERT, OF NEW YORK, N. Y.

WATER-CLOSET.

SPECIFICATION forming part of Letters Patent No. 393,647, dated November 27, 1888.

Application filed March 27, 1888. Serial No. 268,636. (No model.)

To all whom it may concern:

Be it known that I, PHILIP GENGEMBRE HUBERT, of the city and county of New York, in the State of New York, have invented a new 5 and useful Improvement in Water-Closets, of which the following is a specification.

My invention relates to those water-closets in which the water-closet basin or bowl is mounted upon trunnions and contains a soil-receptacle 10 from which a discharge-nozzle leads. When the basin is tilted upon its trunnions or pivots, the discharge-nozzle works downward in a soil-pipe, which receives the contents of the basin; and the object of my invention is to provide for 15 the automatic discharge of a copious supply of flushing-water from a water-tank by the act of tilting the closet-basin to discharge its contents.

The invention will be hereinafter described, 20 and pointed out in the claims.

The accompanying drawing is a vertical section of a water-closet embodying my invention.

A designates the water-closet basin or bowl, which may be of cast metal or of earthenware, 25 and which is mounted upon trunnions or pivots *a*, which are supported in suitable bearings, *b*. As here represented, these bearings spring from a soil-pipe, *B*, and the basin is constructed with a discharge-nozzle, *A'*, which 30 enters downward into the soil-pipe *B* when the basin is tilted upon its pivots or trunnions. The soil-pipe comprises a trap, *B'*, and the basin *A* may have applied to it a handle, *C*, as shown in dotted lines, whereby the basin may 35 be tilted after use, so as to discharge the contents of the basin downward through the discharge-nozzle *A'* and through the soil-pipe *B*. Above the basin *A* is a seat, *D*.

In order to supply the proper water for operating the closet, I employ a tank, *E*, which may be stationary. I have here represented a partition, *e*, as extending transversely across the tank, affording a restricted communication, *e'*, between the upper portion or body of the 45 tank and the compartment *E'* below, which I term the "measuring-compartment." From this measuring-compartment extends a flushing-opening, *e''*, which is closed by a valve, *e''*, and this valve also serves to control communication between the measuring-compartment *E'* and an outlet-compartment, *E''*. When the

valve *e''* is opened, the water escapes, principally, directly through the flushing-opening *e''* and falls into the basin *A*; but a minor proportion of the water passes into the outlet-compartment *E''*, and from this outlet-compartment escapes into the basin *A* through a small hole or nozzle, *f*. As here represented, the valve *e''* is supported by a spring-arm, *e''*, and has a downwardly-extending arm, *e''*, upon 55 which the basin acts when tilted to open the valve *e''*. When the basin *A* is tilted upon its pivots or trunnions to discharge its contents, the rear end of the basin strikes against the push-pin *e''*, and thereby lifts the valve *e''* and 60 opens the flushing-opening. It will be observed that when the basin *A* is tipped it discharges the principal portion of its contents before it strikes the push-pin *e''*; but as soon as the valve is opened a copious supply of flushing-water escapes through the opening *e''* directly into the basin *A*, and thereby serves to 65 flush and thoroughly clean the basin and the trap *B'*.

The restricted openings *e'* do not allow the 70 water to escape downward into the measuring-compartment with anything like the rapidity that it escapes through the flushing-opening *e''*, and consequently the basin is held up until the contents of the compartment *E'* are discharged through the flushing-valve *e''*, and then 75 the basin *A* is allowed to resume its normal position, and the water can flow slowly downward from the body of the tank *E* into the measuring-compartment *E'*, ready for another 80 operation of the closet. While the flushing-valve *e''* is open and the water is flowing freely through the basin *A*, the latter is tipped, and as soon as the basin *A* is returned to its normal position the valve *e''* is closed. During 85 the time that the valve *e''* was open water has escaped through the opening *e''* into the outlet-compartment *E''*, and after the valve *e''* is closed and the basin has resumed its normal position the water will flow from the outlet-compartment *E''* into the basin *A* and will fill the basin 90 with clean water to the desired level.

The supply of water may be kept up in the tank from a pipe, *G*, in which is a cock, *g*, controlled by a float, *g'*, or other self-regulating valve.

Instead of employing the handle *C* for tilt-

ing the basin A, I prefer to employ a means which forms a part of my present invention, and which I will now describe.

F designates a pedal arranged adjacent to the wood casing D', and which may be depressed by the foot either while seated upon the seat D or after rising therefrom. This pedal I connect with the basin A in such manner that when the pedal is depressed it produces the tilting of the basin. As here shown, a lever, F', is fulcrumed at f', and has its rear end connected by a rod, f', with the basin and carries the pedal on its front end. When the pedal is stepped upon, the lever is tilted, and thus tilts the basin.

If the arm or projection e⁵ were arranged upon the basin so as to contact with the valve e' to open it when the basin was tilted, I should consider it the equivalent of the construction shown.

What I claim as my invention, and desire to secure by Letters Patent, is—

1. The combination, with a tilting water-closet basin having a soil-receptacle and a discharge-nozzle leading therefrom upon its front side, of a water-tank above the basin and a valve normally closing a flushing-opening in the bottom of said tank, said valve and basin the one being provided with a projection 30 adapted to come in contact with the other to open the valve upon the tilting of the basin in a direction to discharge the contents of the basin to admit water directly from the flushing-opening into the basin to wash the latter while tilted, substantially as specified.

2. The combination, with a tilting water-closet basin having a soil-receptacle and a discharge-nozzle leading therefrom upon its front side, of a water-tank above the basin and a valve 40 normally closing a flushing-opening in the bottom of said tank, said valve and basin the one being provided with a projection adapted to come in contact with the other to open the valve upon the tilting of the basin in a direction to discharge the contents of the basin to admit water directly from the flushing-opening into the basin to wash the latter while tilted, and an outlet-compartment provided with an opening to said tank normally closed

by the said valve, and a restricted opening for admitting water to the basin, substantially as specified.

3. The combination, with a tilting water-closet basin having a soil-receptacle and a discharge-nozzle leading therefrom upon its front side, of a water-tank above the basin provided with a transverse diaphragm dividing the tank into compartments, and through which extends a contracted opening affording communication between said compartments, and a valve normally closing a flushing-opening in the bottom of said tank, said valve and basin the one being provided with a projection adapted to come in contact with the other to open the valve upon the tilting of the basin in a direction to discharge the contents of the basin, substantially as specified.

4. The combination, with a tilting water-closet basin having a soil-receptacle and a discharge-nozzle leading therefrom, of a foot-pedal arranged to be depressed by a person using the closet, a connection between the said pedal and basin, whereby the operation of the pedal will tilt the basin, a water-tank above the basin provided with a flushing-opening in its bottom, and a valve normally closing said opening, said valve and basin the one being provided with a projection adapted to come in contact with the other to open the valve upon the tilting of the basin by the pedal, substantially as specified.

5. The combination, with a water-closet basin mounted on trunnions and having a soil-receptacle and a discharge-nozzle leading therefrom, of a soil-pipe receiving the said nozzle 85 when the basin is tilted, a tank having a partition forming a measuring-compartment and from which leads a flushing-opening, and an outlet-compartment which has a restricted nozzle into the basin to fill the latter, and a valve, as e', upon which the basin acts in tilting to open the flushing-opening and to fill the outlet-compartment, substantially as herein described.

PHILIP GENGBRE HUBERT.
